UNITED STATES PATENT OFFICE.

RICHARD B. CHARLTON, OF MILWAUKEE, WISCONSIN, ASSIGNOR TO THE
CONTINUOUS RAIL JOINT COMPANY OF AMERICA, A CORPORATION OF
NEW JERSEY.

ROLL.

SPECIFICATION forming part of Letters Patent No. 699,147, dated May 6, 1902.

Application filed June 24, 1901, Serial No. 65,800. (No model.)

To all whom it may concern:

Be it known that I, RICHARD B. CHARLTON, a citizen of the United States, residing at Milwaukee, in the county of Milwaukee and State of Wisconsin, have invented certain new and useful Improvements in Rolls; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to rolls for forming that class of railway fish-plates or rail-joint connections represented by the one shown in Patent No. 427,017, of April 29, 1890, and having a V-shaped extension for inclosing the 20 base-flange of the rail. The objects of the present invention are to provide such rolls having a pass which will roll a bar to be cut up into such fish-plates and deliver the same straight and true, to prevent buckling of the 25 bar and its delivery from the rolls in a crooked and twisted condition because of the great difference in radial distance from the center of the rolls to different points on the walls of the pass, to provide a finishing-pass which 30 will bend up the base-flange of the fish-plate bar without roughening it by a grinding action, to secure a pass having a portion of its walls rotatable independent of the other portions, and to obtain other advantages and results, some of which may be referred to hereinafter in connection with the description of 35 the working parts.

The invention consists in the improved rolls for rolling railway fish-plates or joint connections and in the arrangements and combinations of parts of the same, all substantially as will be hereinafter set forth, and finally embraced in the clauses of the claim.

Referring to the accompanying drawings, 45 in which like characters of reference indicate corresponding parts in each of the several figures, Figure 1 shows in elevation the preparatory or roughing set of a train of fish-plate-forming rolls, and Fig. 2 is the finishing set, 50 the middle roll of said finishing set being

partly in section to more clearly show my invention applied thereto. Figs. 3 and 4 are views of a certain collar from its inner and outer sides, respectively; and Fig. 5 shows in section said collar in place on the roll-spindle. 55

In said drawings, b b^2 b' indicate the top, bottom, and middle rolls, respectively, of a set of roughing or forming rolls, providing between themselves two alternating series of passes 1 2 3 4 5 and 1^a 2^a 3^a 4^a 5^a, respectively, 60 each adapted to gradually shape a bar of iron to approximately the cross-sectional form requisite for fish-plates to be cut therefrom. The bar is then reduced to more exact proportions by a pass 6 (or 6^a) of the finishing-rolls c c' c^2 , (shown in Fig. 2,) and finally the flange adapted to form the base member of the fish-plate is bent by a finishing-pass 7 (or 7^a) 65 into proper angular relation to the foot-member flange. The projection d of the pass enters between said flanges to form the angular space or opening which afterward receives the base-flange of the rail in the completed fish-plate. 70

The passes of the top finishing-roll c are 75 formed on or by rings or sleeves e e' e^2 , &c., fitting nicely on the spindle f of the roll and held to rotate therewith by a key or spline g , a nut h being screwed on the spindle to press said rings or sleeves against the shoulder i and prevent longitudinal displacement. The bottom roll is similarly formed, and it 80 has been common to make the middle roll the same way, the object of the construction being to permit any particular sleeve when worn 85 to be replaced without abandoning the entire roll.

The final or finishing pass 7 (or 7^a) of the rolls forms between a side wall j of the groove on the middle roll and the projection d on the 90 coöoperating roll a space k , which is adapted to bend the base member of the fish-plate into final edgewise position at right angles to the rolls. In this position the great difference in 95 distance of the bottom and outer parts, respectively, of said space k from the center of rotation causes a great difference of speed between said two points, and the tendency has been to buckle the bar and deliver it in a crooked and twisted condition when the walls of the 100

pass were rigid with respect to each other and the roll-spindle. Moreover, a grinding action of the side wall j was produced on the bar, which roughened the bar and rapidly wore away the side of the pass.

By my improved construction I form the ring or sleeve E of the middle roll and which forms the side wall j of the finishing-pass loose upon the roll-spindle f and loose with respect to the sleeve E' and nut h' on opposite sides of itself. This I accomplish, preferably, by the means shown in the drawings, where the key or spline g' , holding the rings or sleeves $E' E^2 E^3$, &c., on the roll-spindle, terminates short of the ring or sleeve E , said ring or sleeve being simply fitted neatly on the spindle and the nut h' being screwed on said spindle outside the ring or sleeve E . Concentric annular grooves $l l'$ are cut in the adjacent faces of the sleeve E and next inner sleeve E' and balls m inserted to reduce friction, and on the outer side of the sleeve E are similar grooves $n o$, adapted to register with grooves $n' o'$ in the nut h' and form bearings for antifriction-balls p . The ring or sleeve E , which forms the right-angular wall j of the finishing-pass, is thus made free to adjust its rotary motion to the bar being delivered and a more perfect product is secured.

Having thus described the invention, what I claim as new is—

1. A roll for rolling metal, having in its periphery an annular pass-groove one side wall of which is formed by a fixed portion of the roll and the other by a loose portion.

2. A roll for rolling metal, said roll presenting an annular peripheral pass-groove, and having an annular fixed flange forming one side wall of said groove and a rotatably-loose ring or sleeve forming the other side wall of the groove.

3. A roll for rolling metal, having two peripherally-projecting flanges forming a pass-groove between themselves, one of said flanges

being fixed and the other being rotatably loose.

4. A roll for rolling metal, having a fixed annular projection and a rotatably-loose ring, said parts having their centers in the same axial line and being adapted to receive metal between themselves.

5. A roll for rolling metal, having at its periphery annular shoulders or projecting walls facing toward each other one of which is fixed and the other rotatably loose with respect to the roll.

6. A roll for rolling metal, having peripherally-projecting annular shoulders or walls adapted to engage the metal in rolling, one of said shoulders or walls being fixed and the other rotatably loose.

7. A roll, having a pass-groove, one side wall of which is fixed with respect to the body of the roll, a ring or sleeve fitted loosely on the body of said roll and forming the opposite side wall of said pass-groove, and means for preventing longitudinal displacement of said ring or sleeve.

8. A roll, having a reentrant pass-groove disposed at or nearly at right angles to the roll, a loose annular or transverse section of the roll forming one side wall of said pass-groove, and means for preventing displacement of said section longitudinally of the roll.

9. The herein-described roll, comprising a body part presenting an outwardly-projecting annular shoulder and having a spindle f , a ring or sleeve e , loose on said spindle and forming between itself and the said shoulder a pass-groove, and a holding-nut h , screwed on said spindle outside the sleeve.

In testimony that I claim the foregoing I have hereunto set my hand this 12th day of June, 1901.

RICHARD B. CHARLTON.
